UNITED STATES PATENT OFFICE.

VESTAL P. COFFIN, OF BOISE, IDAHO.

VALVE MECHANISM FOR INTERNAL-COMBUSTION ENGINES.

1,076,551.

Specification of Letters Patent. Patented Oct. 21, 1913.

Application filed February 2, 1912. Serial No. 875,390.

To all whom it may concern:

Be it known that I, VESTAL P. COFFIN, a citizen of the United States, residing at Boise, in the county of Ada and State of Idaho, have invented new and useful Improvements in Valve Mechanism for Internal-Combustion Engines, of which the following is a specification.

This invention relates to internal combustion engines, and particularly to the valve mechanism thereof, the primary object of this invention being to provide a practicable piston valve for controlling the admission and exhaust of gases to and from the cylinder, doing away entirely with the usual puppet or clap valve now in common use upon nearly all types of gas and gasoline engines.

By the use of the present invention the life and durability of the engine, as a whole, is materially increased, and the efficiency as regards the generation of power is also proportionately increased, in that the valve of this invention is not subject to rapid carbonization, and operates with great smoothness and freedom, it being practicable to lubricate the valve. The invention also does away with the frequent grinding, resetting and timing of the valves now in common use, and also renders the valve practically noiseless.

With the above and other objects in view, the invention consists in the construction, combination and arrangement of parts, as will be hereinafter more fully described, illustrated in the accompanying drawings, and pointed out in the claims hereunto appended.

In the accompanying drawings: Figure 1 is a vertical sectional view through one cylinder of an engine, embodying the present invention. Fig. 2 is a vertical cross section taken on the line 2-2 of Fig. 1, looking toward the admission and exhaust ports. Fig. 3 is a horizontal section taken on the line 3-3 of Fig. 1 when the piston is down. Fig. 4 is a side elevation of a portion of one cylinder, showing the extension which embodies the admission and exhaust orifices. Fig. 5 is a side elevation of the same.

Referring to the drawings, 1 designates the cylinder of an internal combustion engine, 2 the piston working therein, 3 the water jacket, 4 the water space, 5 the spark plug hole, 6 the crank shaft, 7 the connect-

ing rod, 8 the connecting rod bearing and 9 the piston pin.

The parts just herein referred to are illustrative of the usual or conventional form.

In carrying out the present invention, I provide, in connection with each cylinder of the engine, an exteriorly arranged cylindrical casing 10, in which is mounted the reciprocating piston valve 11 of this invention, said valve, as shown in the drawings, reciprocating in a path parallel to the direction of movement of the engine piston 2. At its outer side, the casing 10 is provided with an extension 12 which is inclined, as shown in Fig. 4, so as to dispose the admission port 13 and exhaust port 14 at different elevations with respect to a horizontal plane, the exhaust port being arranged higher than the admission port, as indicated in said Fig. 4, for a purpose which will hereinafter appear. The cylinder is provided with an exhaust port 15, and an admission port 16 arranged also at different elevations, the exhaust port being higher than the admission port, and also offset to one side thereof, as clearly shown in Fig. 2. Furthermore, by reference to Fig. 3, it will be observed that the ports 15 and 16 are inclined in opposite directions, or in other words, the center lines of said ports diverge outwardly, the object being to bring said ports into proper alignment with corresponding ports in the piston valve 11.

The piston valve 11 is provided with an admission port 17 and an exhaust port 18 arranged one above the other, the admission port being on top and the exhaust port below. These two ports extend substantially at right angles to each other, as shown in Fig. 3, and are separated entirely from each other by an intervening web or partition 19. It will further be observed that the admission and exhaust orifices 17 and 14 are flared outwardly or gradually increased in size, the object being to cause the gas to pass more quickly into the cylinder, and the exhaust gases to be carried out from the cylinder with greater rapidity in the back and forth reciprocation of the engine piston 2, which, during one stroke, operates to suck in the gas, and during another stroke, operates to eject the gas through the exhaust port. It will be observed that the exhaust port 14 leading from the cylinder is in a higher plane than the inlet port 13 leading

to the cylinder. The order of the corresponding ports is reversed in the valve, the inlet port 17 being located in a higher plane than the exhaust port 18.

5 In order to impart reciprocatory movement to the piston valve 11 and properly time the same with respect to the ports of the cylinder, and the movements of the engine piston, I provide a cam 20 mounted on 10 and revolving with a rotary cam shaft 21. This cam is provided in one face with a continuous or endless cam groove, embodying an outer loop 22 and an inner loop 23, the two loops intersecting, as shown at 24. Interposed between the cam and piston valve 15 is a rock shaft 25 having fast thereon a lever arm 26 which, at its extremity, carries a double pointed shoe or dog 27 which traverses the convolutions of the cam groove 20 22-23, and is of sufficient length and of proper shape to pass through the intersecting portions at the point 24, without any liability of the same finding its way into the wrong run of the cam groove. Another 25 valve actuating arm or lever 28 is also mounted fast on the rock shaft 25, at the proper point, and is connected pivotally at 29 to one end of the valve stem 30 of the piston valve, said stem being connected pivotally, at 31, to the piston valve. The cam shaft 21 is geared to the crank shaft 6, so as to rotate in the same direction therewith, and at the same speed as the crank shaft.

In operation, starting at the point *a* of 35 the cam groove, when the shoe 27 is at the point *a*, the piston 2 is at the bottom limit of its stroke and the admission port has just closed, the combustion chamber being therefore filled with gas. In the revolution of 40 the cam, when the point *b* reaches the shoe 27, the engine piston 2 has reached the middle of its compression stroke and both ports are closed. In moving from the point *b* around the outer loop and across the intersecting 45 section 24 and up to the point *c*, the piston is completing its compression and also its power stroke, and when the point *c* reaches the shoe 27, the exhaust port starts to open. Moving on from the point *c* to point *d*, at 50 the latter point the exhaust port is fully open. At the point *e* the exhaust port closes, and when the point *f* is reached, the admission port starts to open. At the point *g* the admission port is fully open and remains open during the movement from *g* back to *a*, at which last-named point, the admission valve closes and, as before stated, the engine piston 2 is at the bottom of its stroke. This completes the cycle of movement of the cam 20, also the piston valve 11 and the engine piston 2. In Fig. 1, the piston is rising on the exhaust stroke, the exhaust port starting to close by reason of the piston valve 11 having just started to move 55 downward; the exhaust port in the piston

valve is fully closed at the instant when the top of the piston closes the port in the cylinder.

Any suitable appliance may be used for delivering lubricating material in the proper quantity to the piston valve 11, and as the joint operation between the piston valve and its casing merely controls and alters the relation of ports, there can be no accumulation of carbon, such as is deposited upon the valves and valve seats of internal combustion motors now in common use on automobiles and the like. This insures smooth and easy operation of the valve, greatly increases the life thereof, gives increased efficiency or power to the motor, and practically does away with all valve troubles now so common. The proper timing of the valve is accomplished by the particular form of cam illustrated and described, as it will be observed that the cam has two complete cycles of movement, during each revolution thereof. Furthermore, the timing of the valve is all looked after before the motor leaves the factory, and thereafter it is impossible for the same to get out of timing, another source of much annoyance, trouble, and expense in connection with the gasoline engines at present in use.

What is claimed is:

1. In a four-cycle internal combustion engine, the combination with a cylinder, reciprocating piston and crank shaft, of a piston valve chamber communicating with the cylinder through the medium of independent inlet and exhaust ports, a piston valve working in said chamber and having independent admission and exhaust ports movable into and out of register with independent admission and exhaust ports leading into the cylinder, and mechanism for imparting a complete cycle of movement to the piston valve once only in two revolutions of the crank shaft.

2. In a four-cycle internal combustion engine, the combination with a cylinder, reciprocating piston and crank shaft, of a piston valve chamber communicating with the cylinder through the medium of independent inlet and exhaust ports, a piston valve working in said chamber and having independent admission and exhaust ports movable into and out of register with independent admission and exhaust ports leading into the cylinder, the admission and exhaust ports of the cylinder being arranged at different elevations and the corresponding ports of the valve being also arranged at different elevations, and mechanism for imparting a complete cycle of movement of the piston valve once only in two revolutions of the crank shaft.

3. In a four-cycle internal combustion engine, the combination with a cylinder, reciprocating piston and crank shaft, of a

5 piston valve chamber communicating with the cylinder through the medium of independent inlet and exhaust ports, a piston valve working in said chamber and having
5 independent admission and exhaust ports movable into and out of register with independent admission and exhaust ports leading into the cylinder, and the admission and exhaust ports of the cylinder being arranged
10 at different elevations and the corresponding ports of the valve being also arranged at different elevations but in the reverse order to the ports of the cylinder, the ports of the

valve extending through the valve body at an angle to each other, while the cylinder 15 ports are correspondingly arranged to register therewith, and mechanism for imparting a complete cycle of movement to the piston valve once only in two revolutions of the crank shaft. 20

In testimony whereof I affix my signature in presence of two witnesses.

VESTAL P. COFFIN.
